DESIGN FOR A ROOFING SHEET

Harry L. Olden, Cincinnati, Ohio, assignor to
The Cincinnati Sheet Metal & Roofing Company, Cincinnati, Ohio, a company

Application June 6, 1938, Serial No. 77,621

Term of patent 14 years

To all whom it may concern:

Be it known that I, Harry L. Olden, a citizen of the United States of America and a resident of Cincinnati, Hamilton County, Ohio, have invented a new, original, and ornamental Design for a Roofing Sheet, of which the following is a specification, reference being had to the accompanying drawing, forming a part thereof.

Fig. 1 is a perspective view of a roofing sheet showing my new design, a portion of one corner being omitted therefrom for convenience in illustration.

Fig. 2 is an end view of the roofing sheet, showing the sharp angular relationship of the several elements characterizing my new design.

I claim:

The ornamental design for a roofing sheet, as shown and described.

HARRY L. OLDEN.
